LINK-AND-LINK MACHINE

Charles F. Miller, Philadelphia, Pa., assignor to
Jacquard Knitting Machine Co., Inc., Philadel-
phia, Pa., a corporation of New York

Application November 13, 1945, Serial No. 628,229

5 Claims. (Cl. 66—14)

As is well known, knitting machines of the links-and-links type employ double ended needles, i. e. needles having a hook at each end and jacks to operate these needles in forming stitches and in passing from one needle bed to the other and (usually at least) back again. Speaking generally, the jacks grasp the hooks of the needles and for the most part are moved longitudinally by cams acting on butts projecting from the jacks. The action of such cams may be supplemented, however, by pattern mechanisms, by supplemental jacks acting on the jacks which engage the needles, etc. Sometimes each needle jack is composed of, say, two separate parts, for example, of a needle-pushing portion and a separate hook portion to engage over the needle hook to pull its needle. For brevity, the word "jacks" is used hereinafter to indicate only needle jacks, i. e. those jacks which engage the needles, but it includes such multiple-unit elements as well as unitary jacks composed of a single piece of material.

To release needle from jacks when needles are to be transferred from one needle bed to the other, the head or needle ends of those jacks are lifted from their bed, and very commonly, and perhaps substantially universally in practice, this is done by means of extensions from the needle or head ends of the jacks and cooperating jack-lifting members which move along the needle beds with the feeds for engagement by the jack ends. The action is a camming action, and such jack-lifting members wear relatively rapidly because their jack-engaging surfaces are necessarily rather small and, since there is not more than one jack-lifting member per feed for each needle bed, each jack-lifting member is struck by and called on to lift many jacks in each day's work. Further, the jack-lifting members must actuate the jacks within close limits; wear of only a very small fraction of an inch may cause a failure that results in damage to the machine requiring stoppage of the work until the cause of the failure is found and repairs requiring some time are made. As is well known these jack-lifting members are a source of considerable trouble.

This invention relates to needle jacks and operating means for them that eliminate this trouble to a considerable degree at least.

Briefly to this end, I provide a recess at the back of the tail end of each jack (by which I mean jacks that may be called on to release needles), and preferably one extending for some distance tailward from near the jack butt through which the cams operate the jack. With this I

provide, at each station where a jack may be required to release a needle, a cam to depress the tails of jacks that are to release their needles and thus rock those jacks to raise their heads from the needle hooks. The cam need be only about long enough lengthwise or circumferentially of the needle bed, to hold a jack rocked until it, or its opposing jack in the opposite needle bed, has been moved so far (or both of those jacks have been moved so far) that returning the needle-releasing jack to its initial unrocked position will not re-engage it with the adjacent hook of its needle again. Conceivably such a cam can be movable into and out of action, and thus brought into action only at times appropriate to cause release of needles. Preferably however, I mount such tail cams in fixed positions in the cam systems and at fixed distances from the space for the fabric between the needle beds, and provide the tail of each jack with a butt that is brought to the path of a tail cam only when the jack is brought to its needle-transferring position, e. g., is projected extra far as it were; in the alternative, each jack may be provided with a recess as it were, through which the tail cam or cams can pass without striking the jack so long as the jack is standing or moving in any of its non-transferring positions; in actuality these two are the same. At the head end of a bank of jacks a member or members forming a cam race and/or holding the jacks in their slots, may be recessed to permit the outward movements of the head ends of the jacks that release the needles, or portions of the outer edges of the jacks may be recessed to permit this outward movement of the head ends. In the former case the recess or recesses may be cammed, inclined, transversely of the jacks, to rock the jacks back to their initial positions as a tail cam leaves them; in the latter case the recesses in the jacks may be inclined lengthwise of the jacks so that engagement of these inclines with an adjacent race-forming and/or jack-confining member as a jack is moved from a needle-transferring position, rocks the jack back to its initial position. Or the jacks may be rocked back to their initial positions by action on their tails or in some other way; i. e. the mode of rocking them back to their initial positions is not entirely an essential feature of the invention.

By such an arrangement it is possible to have every needle held firmly by at least one jack at all times, and to have every jack and needle fully confined in a slot in a needle bed at all times.

I am aware that it has been proposed hereto-

fore to rock needle jacks by means of cam elements working on the outer edges of the jacks at both the head and the tail ends. In this prior arrangement however the jacks are within the path of the jack-rocking cams at all times, rather than only when needles are to be transferred from one bed to another, and for considerable periods the needles are not confined to their slots by either of their jacks. Further, a complex form of jack (composed of two separate parts, one rocking on another) is employed, and apparently it is required except in exceptional instances. With my arrangement however a jack may consist wholly of a single piece of metal as before indicated, and every needle can be confined to a slot in the needle beds by at least one jack at all times.

The accompanying drawings illustrate the preferred form of my invention applied to a simple current form of links-and-links circular knitting machine. Fig. 1 is an elevation of the cam system as seen from inside the machine and opened out flat, or it may be a section of the cam system equal in length to one feed length of the machine if the machine has two or more feeds. Fig. 2 is an elevation of the needle jacks employed. Fig. 3 is an elevation of a needle. Fig. 4 is a section of the camming at the line IV—IV of Fig. 1. Fig. 5 is a section on the line V—V of Fig. 1 showing the tail cam. Fig. 6 is a vertical section of a part of one side of the machine about on the line VI—VI of Fig. 1. Fig. 7 is a possible modification of a detail.

As is common practice, two coaxial cylinders 1 and 2 form the needle beds of the machine. These are slotted lengthwise externally to receive the needles and needle jacks, and are spaced apart at 3 to permit the passage of the fabric from the needles to the interior of the lower cylinder 1 as the fabric is formed. Forecuts attached to the adjacent edges of the needle cylinders are shown at 4. Cam cylinders 5 and 6, one mounted outside each needle cylinder, Fig. 6, carry the members of the cam system shown in Fig. 1. For simplicity of description it will be assumed that the needle cylinders 1 and 2 are stationary and that the cam cylinders 5 and 6 rotate about them, although the opposite may be the case in any instance as will be understood from prior practices. The latch needles 7 (Fig. 3) may be conventional; being double ended, i. e. having a loop-forming hook and latch at each end, they are transferable by endwise movement, from one bed 1 to the other 2 and vice versa, as is distinctive of links-and-links machines.

As common, two needle jacks 8, one in each needle bed 1 and 2, are provided to operate each needle 7; they lie in the slots of their respective needles and for the most part the members of the cam system lie close to the outer edges of the jacks so as to confine the jacks in their slots (and therewith the needles as will be understood from what follows), as indicated at the upper end of Fig. 6. These jacks 8 are substantially straight members as shown in Fig. 2, and are of an appropriate thickness as will be understood from prior practices. The head portion of each of these jacks has a shoulder 9 to engage an end of a needle for pushing the needle, and a projection 10, in the form of a hook or otherwise, to pass over a needle hook whereby the jack can pull the needle (see Fig. 6). Also at a point removed from the head portion each jack has a butt 11 for engaging in the cam races whereby the jack (and therewith its needle) is actuated.

The foregoing regarding jacks is substantially conventional. In addition however the jack 8 is provided with a tail portion 12, which places its operating butt 11 at a mid-portion of the jack as it were. The back of this tail portion is cut away to provide a recess at 13 to permit the jack to be rocked in its slot to the extent necessary to carry its hook-engaging portion 10 completely out of the hook recess in which it may be engaged, as shown in Fig. 6. Preferably the recess is so placed that the rocking is about a fulcrum near the operating butt 11, say about as shown. It is evident that the recess or cutout 13 may be of any one of various shapes and sizes; substantially any shape and size is satisfactory that will permit the jack to be rocked to remove its projection 10 from its needle. Also each of the jacks 8 is provided with an outwardly projecting butt 14 on its tail portion 12. Preferably the outer edge or face of this butt 14 is on about the same line as the outer edge 15 of the jack, so that for the most part the outer edge of the butt 14 also remains close to the inner faces of cam members. Between the butts 11 and 14 the outer edge of the tail portion 12 of the jack is depressed as it were, so that the cams 16 and 52, which project inwardly from the cam system, can pass over the jacks at this region (or be passed over by the jacks, if the machine is one in which the needle cylinders rotate) without striking the jacks. The walls of the needle-and-jack slots may be cut out locally at the paths of these tail cams as indicated at 19 in Fig. 6 to permit such cams to extend into the slots. In the present instance the tail cams 16 and 52 (and others if there are any) are fixed in position in and with respect to the cam system and at fixed distances from the fabric space 3 between the needle beds, and the tail portions 12 of the jacks are of such lengths that the tail butts 14 remain outside the path or paths of the cam 16 (or tail cams, e. g. 16 and 52) except when the respective jack is projected to needle transferring position as indicated in Fig. 6. As indicated before however, it is not altogether necessary that the tail cams such as 16 and 52 be fixed in the cam system and carried at fixed distances from the fabric space 3. Should the tail cams not project into the slots at all times, the recesses between the jack butts 11 and 14 might be omitted, and in such a case the so-called tail butts 14 would not (or at least need not) stand out as separate entities in the manner illustrated in Fig. 2, but undemarked portions of the back edges of the jack tails might serve the same purpose and in fact constitute tail butts. Where tail butts are mentioned in the claims hereafter, such constructions are to be understood as included.

Preferably also a portion 17 projects from the head portion of each jack to hold needle latches open (cf. Fig. 6), and preferably the outer end of the portion 17 from its inner edge to its outer edge, is inclined toward the operating butt 11 as shown at 18 in Fig. 2. These inclines at 18 provide cams or wedges for opening adjacent latches of the corresponding needles 7 at appropriate times when there are no yarn loops on the needles to open the latches. Speaking generally however these are matters of preference only.

Also speaking generally the relations of each two opposing needle jacks to their needle and to each other are substantially conventional and as customary heretofore in links-and-links machines as will be appreciated from Fig. 6. Also it will be understood from what has been said

before that the structure and races of the cam system illustrated in Fig. 1 are to be regarded as representative and the invention not limited to it except, preferentially, at the needle transferring stations. It is immaterial, too, of course whether or not the cam system is composed of the particular number and shapes of blocks illustrated in Fig. 1, etc.

However, in the cam system illustrated the jacks are brought (by their operating butts 11) to their most retracted positions at 25 and 26 by the stitch cams 27 and 28, and in coming to these positions their needles cast off previously drawn loops of course. From 25 and 26 the cams are projected to rest positions 29 and 30, and if desired the jacks of one or both beds may thereafter be projected as at 31 and immediately retracted again to permit the yarns and loops to readjust themselves, i. e. tensions to equalize, before being subjected to further action. In the present instance in each section the cam race for the operating butts 11 has a portion 33 or 34 whereby the jacks may be carried completely through the section or a feed in retracted positions in which any needles that may be held by the respective jacks are entirely out of operation and merely hold any loops that may be on them; these idle race portions 33 and 34 are simply to permit the formation of certain types of fabrics or stitches. In either forming stitches or transferring however the butts 11 proceed from 29 or 30 (or from 31) to race portions 35 and 36 where (because of the needle extension 17 and their head inclines 18) a jack in the upper race portion 36 serves to open or assures the opening of an upper latch of a needle held by a jack in the lower race portion 35 or vice versa, if there is no yarn loop in the particular hook at the moment, or if a loop has failed to open the latch of its hook; i. e. in these race portions the wedge end 18 of a jack not carrying a needle is forced between the adjacent latch and hook of its needle (which for the moment is being carried by the respectively opposing jack) and thus forces the latch open if it is not open already. Gate cams 37 and 38 direct the jack butts 11 to 35 or 36 in lieu of 33 or 34, or vice versa; these may be adjusted as indicated by the arrows on them, to direct some or all of the jack butts 11 of their respective races into either of the two adjacent race portions. Beyond 35 is a transfer point for transferring needles from the lower bed 1 to the upper bed 2.

In order that needles may be transferred up or retained in the lower bed as desired, the race of the lower cam cylinder is divided into two parallel race portions 39 and 40 at this point, separated by a transfer cam 41. The gate cam 42 in the present instance, movable as indicated, serves to direct butts 11 of the jacks 8 of the lower needle bed 1 into either 39 or 40 at will. However other means can be used for directing the lower jacks into either 39 or 40, and either selectively or en masse as it were, as will be understood from prior practices. Such jacks as are directed to the race portion 39 retain any loops they may be carrying and proceed with them toward the yarn guide which feeds yarn to the hooks at a later stage as described hereafter. On the other hand lower jacks that pass over the transfer cam 41, i. e. travel 40, transfer any needles they may be carrying to their respectively opposing jacks in the upper needle bed. To bring about this action, the operating butts 11 of the upper jacks pass from their race portion 36

to a portion 44 where the upper jacks are projected so far that the adjacent hooks of needles being carried by lower jacks passing upward to and over the transfer cam 41, are thrust underneath the upper jacks to a point where these hooks pass above the projections 10 of the upper jacks and accordingly are grasped by the upper jacks; the relative positions are shown in Fig. 6. At 40 the jacks are projected extra far, as I call it. To enable the needle hooks to pass underneath the projections 10 of the upper or receiving jacks, the head portions of the corresponding jacks must be raised of course, or allowed to rise. It is sufficient to simply allow them to rise under the thrust of the entering needles. To permit this displacement of the head and mid-portions of the upper jacks, the upper race-forming member, adjacent the jack heads, is recessed throughout that length of it which passes over a jack while the jack is rising to admit a needle and falling again; i. e. is cut out for about the length of the race represented by the bracket 45, and in a manner generally similar to the cutout 46 of Fig. 4. Preferably this cutout at 45 is made as short as possible so that as soon as the upper jack can be rocked back fully into its slot again, the race-forming member or members will again be close to the outer edge of the slot walls to confine jacks and any needles they may hold to their slots. Just beyond the transfer cam 41 the lower race inclines at 47 to retract the jacks which have transferred their needles to the level of the race portion 39, as will be observed from Fig. 1. Before this retraction of a lower jack that has delivered a needle to an upper jack is begun however, the lower jack must be detached from the needle, and it must be held detached until the needles and jack have reached such relative positions that they cannot engage again. To this end the lower race-forming member, adjacent the head portions of the lower jacks, is recessed or cut out as at 48, and the tail cam 16 is provided, extending into the slots of the lower needle bed 2, and lengthwise extending over substantially the same length of the cam system as the cutout 48, to engage the tail butts 14 of the jacks that have been projected to the transferring position and thereby rock those jacks to needle-releasing positions, Fig. 6, and hold them rocked until their butts 11 have passed sufficiently far down the incline 47 to place the projections 10 of the respective jacks below their adjacent needle hooks. The cutout 48 is of an appropriate length and shape to permit this rocking of the lower jack, as will be understood from Figs. 1 and 4.

The lower jack is returned by incline 47 to the race level 39, and angularly immediately behind this point the upper cam race may be provided with a needle-transferring apparatus, e. g. a transfer cam 50, a cutout 51 in the upper race-forming members corresponding generally to the cutout 48, a tail cam 52 like the tail cam 16, a gate cam 53 generally like the gate cam 42 to direct the operating butts 11 of the upper jacks into either the race portion 54, say corresponding generally to 39, and a further projected race portion 55 corresponding generally to 40, and also the race-forming members of the lower cam cylinder provided with the cutout 46 before mentioned to permit the lower jacks to be rocked to admit needles coming down to them from the upper needle bed. Such an arrangement permits needles to be transferred from the upper

to the lower needle bed as directed by the gate 53 or whatever may be used in its place.

From the race portion 39 and 54 the lower and upper jacks are retracted to the levels 55 and 56 respectively. Needles in the lower bed pass through clearing position as their jacks are carried to the race portion 39 (or 40), and likewise needles in the upper needle bed pass through clearing position as their jacks pass toward the race portion 44. At the 39 and 44 levels therefore the previously drawn loops are at mid-portions of the needles as will be apparent from Fig.

6. At the 55 and 56 levels all the needles, whether carried by upper jacks or lower jacks, stand at the proper levels to receive yarn fed through the eye 51, the yarn actually reaching any needle at about the position 58, say. The yarns may be delivered by the yarn eye or guide 57 either, say, into the needle hooks or onto the open latches of the needles. As the upper and lower jacks next are retracted further by the stitch cams 27 and 28, the various needles form new loops of course, each to one side or the other of the fabric depending on whether the particular needle is carried by an upper jack or a lower jack, as will be understood from prior practices.

At 59 a latch plate serves to hold open the latches of the needles approaching the yarn at 58, i. e. regardless of whether the latch is an upper latch or a lower latch, the needle being in a lower jack or an upper jack.

The trailing side of any of the cutouts 45, 46, 48 and 51 may be shaped to engage the jacks to rock them back into their initial positions in their slots at the proper moments, or other means may be provided to return rocked jacks to their initial positions so far as this may be necessary. Preferably however the advance sides and mid-portions of the cutouts 45, 46, 48 and 51 are so shaped that at every place they only just substantially permit the rise required of the jack heads under the actions of the needles thrusting beneath them (at 45 and 46) or under the action of the tail cams 16 and 52 (at the cutouts 48 and 51), and the trailing sides of the cutouts either rock the jacks back to their initial positions as soon as that is possible, or follow closely the jack heads as they are rocked back by other means. With such shaping of the cutouts the jacks (and thereby the needles) are confined closely to their slots at all times.

Fig. 7 illustrates one of the possible modifications of the structures so far described. Namely, one rendering the cutouts 48 and 51 unnecessary. To this end, each jack 8 is provided, at its outer edge, with a recess 60 deep enough to permit its head to rise away from a needle hook without recesses in the cam members, but, preferably, leaving an edge portion 61 to be engaged by the cam members when the respective jack is in all positions except that of transferring. Between the recesses 60 and the edge portions 61, the edge portion 62 may be inclined inwardly as shown in Fig. 7, so that on the retraction of the jack by a cam incline 47 or a corresponding incline in the upper race, this incline at 62, riding on the cam member, causes the jack to be rocked back to its initial position.

The operations of the mechanisms illustrated have been described in connection with the constructions and need not be repeated.

It will be observed that my invention provides large cam surfaces for raising the jack heads from their needles, namely, the extended surfaces at such tail cams as 16 and 52, with the result

that the wear is relatively slow. Further, the arrangement is such that the race-forming members of the cam system completely confine (or at least can be arranged to confine) the jacks to their slots in such a manner that every needle is held confined to one or the other of its slots by at least one of its jacks at every moment.

As indicated before, my invention is not to be understood as limited to the details of construction and operation shown in the drawings and described above, except as appears hereafter in the claims.

I claim:

1. In a knitting machine the combination with two needle beds having a fabric space between them, a plurality of needles transferable from one bed to the other, needle jacks in one of said beds and cams to move needle jacks of the machine to needle-transferring positions, of needle jacks in the other of said beds that are recessed at the backs of their tail portions to permit rocking of those jacks to release needles, and a cam movable, relative to the latter jacks, transversely thereof, to engage successively the tail portions of such of the latter jacks as are moved to needle-transferring position to thereby rock the same to release their needles and hold them rocked until there has been such jack retraction that the rocked jacks can be restored to their unrocked positions without reengaging the needle hooks.

2. The subject matter of claim 1, characterized by the fact that said cam is fixed in position in the cam system of the machine and said recessed jacks are provided with butts that are brought to the path of said cam as those jacks are moved to needle-transferring positions.

3. In a knitting machine, the combination with two needle beds having a fabric space between them, a plurality of needles transferable from one bed to the other, needle jacks having butts in each of said beds, and members providing a cam race for the butts of the needle jacks in each of the beds and extending along the needle beds close to said jacks to confine the jacks in the beds, characterized by the fact that needle jacks of at least one of said beds are provided with recesses at the backs of their tail portions to permit them to rock to release their needles and at their tail portions are provided with outwardly projecting butts, a cam, fixed in position with respect to said race-providing members, is disposed to engage said tail butts to depress the tails to rock jacks when the respective jacks are projected to their needle-transferring positions and hold them rocked until there has been such jack retraction that the rocked jacks can be restored to their unrocked positions without engaging the hooks of their needles, and the portion of said race-forming members adjacent the heads of the recessed jacks being recessed to receive the head portions of jacks rocked by said cam.

4. In a knitting machine, the combination with two needle beds having a fabric space between them, a plurality of needles transferable from one bed to the other, needle jacks having butts in each of said beds, and members providing a cam race for the butts of the needle jacks in each of the beds and extending along the needle beds close to said jacks to confine the jacks in the beds, characterized by the fact that needle jacks of at least one of said beds are provided with recesses at the backs of their tail portions to permit them to rock to release their needles

and at their tail portions are provided with outwardly projecting butts, a cam, fixed in position with respect to said race-providing members, is disposed to engage said tail butts to depress the tails to rock jacks when the respective jacks are projected to their needle-transferring positions and hold them rocked until there has been such jack retraction that the rocked jacks can be restored to their unrocked positions without engaging the hooks of their needles, and the head portions of said recessed jacks being provided with recesses at their outer edges to permit said head portions to be rocked when projected to needle-transferring positions, said recesses having inclines to rock the jacks back to their initial positions as the jacks are retracted.

5. In a knitting machine, two coaxial needle cylinders having a fabric space between them, a plurality of slidable double-ended needles transferable from one cylinder to the other, needle jacks in each of said beds, said jacks having outwardly projecting butts at their mid-portions and at their tail portions and being recessed at the backs of their tail portions to permit the jacks to be rocked to release their needles, members encircling said cylinders close to the jacks therein to confine the jacks in the cylinders and providing races for the mid-portion butts of the two sets of said jacks, the race for each set including a portion retracting the respective jacks to a cast-off position, a portion projecting the jacks at least toward clearing position, a portion holding the jacks in projected positions and a

10

portion paralleling the last mentioned portion projecting the respective jacks to and retracting jacks from needle-transferring positions, cams to direct jacks to one or to the other of the last 5 mentioned two race portions at will and a cam for the tail butts of each of said two sets of jacks and at a fixed distance from said fabric space, said cams occupying substantially the same angular positions as at least a part of the last mentioned jack-retracting portions of said races and engaging said tail butts when the jacks are at said jack-retracting race portions, the portion of said encircling and race-providing members adjacent the head portions of each of said two sets of jacks being recessed to receive the heads of rocked jacks at substantially the same angular position as the respectively adjacent tail-butt cam.
